CLAIM

I claim the ornamental design for a guitar string wrap, as shown and described.

DESCRIPTION

FIG. 1 is a top perspective view of a guitar string wrap showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, the guitar string wrap shown attached to a guitar.

The guitar string wrap is shown with a symbolic break in portions of its length in FIGS. 1-5 and 8. The appearance of any portion of the device between the break lines forms no part of the claimed design. In addition, the broken lines in FIG. 2 showing the perimeter of a hook-and-clasp material define the bounds of the claimed design and form no part thereof, and the broken dotted lines within such perimeter showing the location of such hook-and-clasp material also form no part of the claimed design. The broken lines in FIG. 8 showing a guitar are for the purpose of illustrating environmental structure only and form no part of the claimed design.
